(57) **CLAIM**

The ornamental design for a bottle with cap, as shown and described.

DESCRIPTION

FIG. 1 is a front elevational view of a bottle with cap showing our new design, the left side, right side, and rear elevational views being identical thereto;

FIG. 2 is a top view thereof; and,

FIG. 3 is a bottom view thereof.

The broken lines in the drawings illustrate portions of the article that form no part of the claimed design.
